CLAIM

The ornamental design for a storage container for
motor oil or the like, as shown and described.

DESCRIPTION

FIG. 1 is a rear-elevational view of a storage container
for motor oil or the like showing my new design;
FIG. 2 is a front-elevational view thereof;
FIG. 3 is a left-side perspective view thereof;
FIG. 4 is another left-side perspective view thereof;
FIG. 5 is a bottom plan view thereof;
FIG. 6 is a top plan view thereof; and
FIG. 7 is a right-side elevational view thereof.

FIG. 7

FIG. 2
